COMBINATION SCREWDRIVER, CAP REMOVER, ENVELOPE OPENER, AND NAIL FILE

Nicholas Joannides, Ames, Iowa

Application July 15, 1952, Serial No. 20,614

Term of patent 14 years

(Cl. D44—29)

To all whom it may concern:

Be it known that I, Nicholas Joannides, a citizen of the United States, residing at Ames, county of Story, State of Iowa, have invented a new, original, and ornamental Design for a Combination Screwdriver, Cap Remover, Envelope Opener, and Nail File, of which the following is a specification, reference being had to the accompanying drawing, forming a part hereof.

Figure 1 is a face view of a combination screwdriver, cap remover, envelope opener, and nail file, showing my new design;

Figure 2 is an edge view;

Figure 3 is a view opposite to that shown in Figure 1; and

Figure 4 is an end view.

I claim:

The ornamental design for a combination screwdriver, cap remover, envelope opener, and nail file, as shown.

NICHOLAS JOANNIDES.
